US0D1074277S

(12) **United States Design Patent** (10) **Patent No.:** **US D1,074,277 S**
(45) **Date of Patent:** **** May 13, 2025**

(54) **DISPLAY RACK**

(71) Applicant: **Jiwei Wu**, Zhejiang (CN)

(72) Inventor: **Jiwei Wu**, Zhejiang (CN)

(**) Term: **15 Years**

(21) Appl. No.: **29/973,623**

(22) Filed: **Nov. 18, 2024**

(51) **LOC (15) Cl.** **06-04**

(52) **U.S. Cl.**

USPC **D6/682.4**

(58) **Field of Classification Search**

(57) **CLAIM**

The ornamental design for a display rack, as shown and described.

DESCRIPTION

FIG. 1 is a perspective view of a display rack showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the display rack that form no part of the claimed design.

1 Claim, 8 Drawing Sheets
